UNITED STATES PATENT OFFICE

LOUIS SZATLER, OF HAMMOND, INDIANA, ASSIGNOR OF ONE-HALF TO ARANKA CZANK, OF HAMMOND, INDIANA

BANK PROTECTOR

Application filed July 29, 1932. Serial No. 625,801.

This invention relates to certain new and useful improvements in bank protectors.

The primary object of the invention is to provide a bank protector in the form of a shield or guard plate adapted to be shifted into operative position for closing the window opening of a bank teller's compartment for the protection of the bank teller in the event of attack from a bank robber or other persons, the protector and its operating mechanism being disposed rearwardly of the front wall of a bank teller's compartment or cage and obscured from view as well as being automatically operated for instant closing of the window opening.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a fragmentary front elevational view of a partitioned wall in a bank showing the grate bar window opening fronting the bank teller's cage;

Figure 2 is a vertical cross-sectional view through the partitioned wall carrying a manually operable device adjacent the floor rearwardly of the wall for placing the protector in set position;

Figure 3 is a fragmentary rear elevational view of the partition wall facing the bank teller's compartment with the protector illustrated by dotted lines in set position and showing the pedal adjacent the floor for the release of the protector;

Figure 4 is a fragmentary rear elevational view, similar to Figure 3, showing the protector in its operative position for closing the window of the bank teller's compartment;

Figure 5 is a front elevational view of the partition facing the bank teller's compartment, partly broken away and shown in section to illustrate tension devices for moving the protector to operative position and the manually controlled devices for holding the protector in set position;

Figure 6 is a vertical cross-sectional view taken on line 6—6 of Figure 3; and

Figure 7 is a horizontal sectional view taken on line 7—7 of Figure 3, showing the side guide for the window protector.

Referring more in detail to the accompanying drawings, there is illustrated a bank protector associated with the grated window opening 10 in the front wall 11 of the partition 12 forming the bank teller's compartment, the outer side of the front wall 11 carrying the usual shelf 13 at the lower end of the grated window opening 10. The partition 12 rises from the floor 14 and carries a horizontal head bar 15 at its upper end. 60

A casing containing the protector for the grated window opening 10 and the operating mechanism for the protector is suitably secured to the rear side of the front wall 11 and as shown in Figure 7, comprises a bottom wall 16 flatly engaged with the wall 11 and a top wall 17 spaced from the bottom wall by edge flanges 18 and secured to the bottom wall by screw bolts 19 or other fastening devices. The casing for the protector and its operating mechanism occupies the entire area of the rear side of the front wall 11 and is provided with an opening 20 therein registering with the grated window opening 10, the top wall 17 of the casing carrying a shelf or counter 21 at the base of the opening 20 and aligned with the outer shelf 13 as shown in Figure 2. 75

The protector comprises a guard plate 22, preferably of rectangular form and of a size to close the grated window opening 10 when in operative position, having upper and lower edge flanges 23 and 24 respectively and carrying at each end a substantially cylindrical bearing block 25 vertically slidable in the tubular guides 26 offset from the bottom wall 16 of the protector and mechanism casing as shown in Figures 5 and 7 and engaged with coil springs 27 set into the lower ends of the tubular guides 26, the springs 27 normally acting to influence the guard plate 22 in an upward movement to extend across the window opening 20 in the top wall 17 of the casing and to close the grated window opening 10. A spring or shock absorbing device is associated with the guard plate 22 to cushion the closing movement of the guard plate relative to the grated window opening and as shown in Figure 5, the stop block 28 rising centrally of the upper flange 23 of the guard plate 22 moves into engagement with the pin 100 29 set into the head bar 15 of the partition 12 and tensioned by the spring 30. 100

The mechanism for placing the protector or guard plate 22 in set position against the tension of the operating springs 27 and 110

the release devices for the mechanism to permit operation of the springs is confined within the lower end of the mechanism casing and includes a horizontal shaft 31 disposed below the tubular guides 26 and guard plate and is supported at its ends in bearings 32 and 33. The portion of the shaft 31 disposed below and between the tubular guides 26 has a toothed clutch element 34 rigid therewith 5 and a cooperating clutch element 35 free on the shaft 31 normally influenced into engagement with the rigid clutch member 34 by means of the coil spring 36 engaging the free clutch element 35 at one of its ends and engaged at its other end with the abutment disk 37 on said shaft. A pair of cables or cords 38 are fixed at one end as at 39 to the lower edge flange 24 of the guard plate 22 in spaced relation with the other ends of the cords 38 10 and secured to and wound upon the shaft 31 as at 40. The operating means for the shaft 31 include a bevel gear 41 fixed to the shaft 31 adjacent the bearing 32 that is in meshing engagement with the bevel gear 42 fixed to the 15 shaft 43 that is journaled in the angularly offset bearing 44 carried by the lower end of the mechanism casing. The outer end of the shaft 43 is of T-formation as at 45 with which a key or crank 46 is engageable as 20 shown in Figure 2 to effect operation of the shaft 43 and rotation of the shaft 31. A bell crank lever is pivotally mounted as at 47 upon the bottom wall 16 of the mechanism casing and has the leg 48 thereof forked for 25 engagement with the free clutch element 35 as at 49 while the other leg 50 of the bell crank lever is of angle formation and extends through the slotted opening 51 in the top wall 17 of the mechanism casing adjacent 30 the floor 14 and carries an operating pedal 52 disposed within the bank teller's compartment.

To lower the guard plate 22 to set position shown in Figs. 3 and 5, the crank 46 is engaged with the shaft 43 to effect rotation of the shaft 31, the cords 38 attached to the guard plate being wound upon the shaft 31 as shown in Fig. 5 for lowering the guard plate against the tension of the springs 27. 45 During this rotation of the shaft 31, the free clutch elements 35 automatically escape from engagement with the clutch element 34 fixed to the shaft 31 and when the guard plate 22 has reached its limit of lower movement, 50 reverse rotation of the shaft 31 is prevented by engagement of the two clutch elements 34 and 35, the latter restraining the clutch elements 34 and shaft against rotation by reason of the mounting of the bell crank lever leg 48 upon the bottom wall 16 of the mechanism casing. In the presence of impending danger to the bank teller, the pedal 52 is depressed 55 for disengaging the clutch element 35 from the clutch element 34 against the tension of the spring 36, thus freeing the shaft 31 and

permitting the springs 27 to shift the guard plate 22 in an upward direction to close the window opening 20 and the grated window opening 10, impact of closing movement of the guard plate being absorbed by the tensioned pin 29 set into the head bar 15 of the partition 12. The setting and releasing devices for the operating mechanism for the guard plate are located at the inner side of the front wall 11, entirely hidden from view so that the front wall 11 at its outer side presents the usual appearance of a bank teller's compartment.

While there is herein shown and described the preferred embodiment of the invention, it is nevertheless to be understood that minor changes may be made therein without departing from the spirit and scope of the invention as claimed.

I claim:

1. Operating means for a bank protector wherein a sliding guard plate is adapted to be spring raised to closed position relative to a bank teller's window, means for holding the guard plate in set position out of registry with the window including a manually rotatable shaft, cord connections between the shaft and guard plate, a clutch element fixed to the shaft, a cooperating clutch element loose on the shaft and normally engaged with the fixed clutch element and manually operable means associated with the loose clutch element to prevent rotation thereof and to disengage the same from the fixed clutch element to permit rotation of the shaft and closing of the guard plate relative to the window, the operating means for the loose clutch element including a bell crank lever, one leg of the lever engaged with said loose clutch element and the other leg of the lever being of angle formation and a pedal on the last named end of the lever.

2. Operating means for a bank protector wherein a sliding guard plate is adapted to be spring raised to closed position relative to a bank teller's window, means for holding the guard plate in set position out of registry with the window including a manually rotatable shaft, cord connections between the shaft and guard plate, a clutch element fixed to the shaft, a cooperating clutch element loose on the shaft and normally engaged with the fixed clutch element, manually operable means associated with the loose clutch element to prevent rotation thereof and to disengage the same from the fixed clutch element to permit rotation of the shaft and closing of the guard plate relative to the window, a bevel gear on the shaft, an angular bearing offset with respect to the shaft, a manually operable shaft in the offset bearing and a bevel gear on the last named shaft having meshing engagement with the aforesaid bevel gear.
